UNITED STATES PATENT OFFICE.

EDMUND W. ZEH, OF NEWARK, NEW JERSEY.

POWER-PRESS.

1,151,845.

Specification of Letters Patent. Patented Aug. 31, 1915.

Application filed December 31, 1914. Serial No. 879,845.

To all whom it may concern:

Be it known that I, EDMUND W. ZEH, a citizen of the United States, residing at Newark, in the county of Essex and State of New Jersey, have invented certain Improvements in Power-Presses, of which the following is a specification.

This invention relates to that class of power presses in which a head for carrying the upper die is moved up and down by a screw, said screw being rotated by a friction wheel at its upper end adapted to be driven in one direction or the other by opposite drive disks.

The objects of the invention are to provide an improved press of this character; to secure improved means for shifting the drive disks into and out of engagement with the friction wheel; to avoid as far as possible reciprocating parts in the shifting mechanism; to provide a control rod to shift the drive disks by a rotary movement; to adapt this control rod to be operated either by foot treadle or by hand independent of the foot operating means, the operation in either case shifting the drive disks to cause the head to be lowered; to provide improved foot operating means for starting the press; to automatically rotate said control rod as the head approaches its lower position, so as to shift the drive disks and cause the head to be raised; to obtain improved means for automatically stopping the hammer at the end of its upstroke without undue oscillation; to make said means readily adjustable; to provide means for causing continuous operation of the machine when so desired; to provide means for quickly changing from such continuous operation to single blows, so that the hammer will become stationary at the end of its upstroke; to provide means for adjusting the fixed positions of the drive disks upon their shaft; to automatically dislodge or knock the work from the lower die after being stamped; to provide such dislodging or knock-out means which will not interfere with placing a fresh blank upon the die; to secure simplicity of construction and operation, and to obtain other advantages and results as may be brought out in the following description.

Referring to the accompanying drawings, in which like numerals of reference indicate the same parts throughout the several views, Figure 1 is a perspective view of my improved power press in idle position with

the hammer up; Fig. 2 is a section of the bed of the machine taken on a central vertical plane from front to back and showing certain starting mechanism; Fig. 3 is a rear view of said starting mechanism; Fig. 4 is a detail perspective view of the friction wheel brake; Fig. 5 is a central vertical section taken on a plane from front to back of the press; Fig. 6 is a front elevation of a portion of the press showing means for causing continuous operation thereof; Fig. 7 is a sectional view on line A—A of Fig. 6, and Fig. 8 is a central section through one of the drive disks and shaft, showing the adjustable mounting of said disk.

In the specific embodiment of the invention illustrated in said drawings, I indicates the frame of my improved press, preferably mounted upon legs 2, 2 to elevate it to a suitable and convenient height. Said frame 1 is centrally open, providing a vertical slideway for a head or hammer 3 carried upon the lower end of a screw 4 which works through the top of said frame and has fixed upon its upper end above the frame a horizontal wheel 5 providing at its periphery a friction surface. The said hammer 3 is adapted to carry at its lower end a die, not shown, and the frame 1 forms at the bottom of its central opening a bed 6 to receive the work upon a lower die 7 adapted to cooperate with the other die on the hammer. In order to raise and lower the head or hammer to secure the necessary pressure or impact of the dies, the screw 4 is alternately rotated in opposite directions by the following means.

Above the friction wheel 5 a horizontal shaft 8 extends diametrically of said wheel, and is journaled in brackets 9, 10 bolted to and projecting upward from the frame 1 at opposite sides of the machine. This shaft is provided at one end outside the bracket 9 with fast and loose pulleys 11 and 12 adapted to receive a driving belt (not shown) and which belt can be moved from one pulley or the other by a belt shifter 13. Between the bearings of said shaft in the brackets 9, 10 a pair of drive disks 14 and 15 are mounted fast upon said shaft at diametrically opposite sides of the horizontal wheel 5 and spaced far enough apart

that in normal or neutral position neither disk will engage the said horizontal wheel. The shaft 8 is slidable in its bearings; however, whereby either of the disks may be brought into engagement with the horizon-

tal wheel to rotate the same and raise or lower the screw as is customary in the art.

- Outside of one of the brackets supporting the shaft 8, and here shown between the bracket 9 and the driving pulleys 11, 12, two collars 16, 16 are made fast upon the shaft 8 by set screws or the like, and between said collars is a sleeve 17 rotatably loose upon the shaft and having trunnions 18 received by the 10 forked end 19 of a lever 20 which is fast upon a transverse rock shaft 21 rotatably mounted in an arm 22 of the bracket 10, so that said lever 20 may swing in a plane of the driving shaft 8, preferably a vertical plane 15 or substantially so. To the lower end of the lever 20 is pivotally attached a link 23 extending in the same general direction as the driving shaft 8 toward the center of the press, and pivotally connected at its inner 20 end to the free end of a crank 24. Said crank is shown as rotatable in a horizontal plane and carried on the upper end of a control rod 25 vertically disposed at the front of the frame 1 and at one side of the 25 central opening of said frame, said crank being fast with respect to the control rod so that the drive disks may be shifted by rotating the control rod. At its lower end, the control rod 25 passes through the flaring 30 base of the frame 1, which provides thereat a lower bearing 26, and at its top the control rod is mounted in an upper bearing 27 in alignment with said lower bearing. The crank 24 on the upper end of the control rod 35 may rest upon the top of the upper bearing 27, if desired, and thereby prevent the control rod from dropping down. Near the lower end of the control rod 25 and preferably above its lower bearing, is a hand 40 lever 28 extending horizontally in front of the bed 6 rotatably fast upon said control rod and of a length sufficient to afford adequate leverage when grasped at its free end to rotate the control rod 25 and shift the 45 drive disks. Preferably, this lever lies transversely of the press, close to its base or bed, and when both of the drive disks 14, 15 are out of engagement from the horizontal wheel 5 said lever lies at its middle 50 or neutral position. From this neutral position the lever may be swung inward to cause the screw to be lowered, or may be swung outward from this neutral position to cause the screw to be elevated, it being 55 understood that returning the lever to and retaining it in its middle position will throw both driving disks 14, 15 off the friction wheel 5. Obviously the entire range of movement of the lever 28 is small.
- 60 In operation of the construction shown, the driving disks 14, 15 are rotated with their tops advancing toward the front as indicated by the arrow in Fig. 1, and the screw 4 having a left hand thread, the disk 65 15 nearest the right hand side of the ma-

chine, that is, nearest the shifting lever 20, becomes the lowering disk and the other disk 14 the elevating or raising disk. Means are preferably provided for normally pressing or shifting the raising disk 15 toward the friction wheel 5, so that unless said disk is positively held out of engagement therefrom the hammer will be raised. The means here shown, and more particularly described and claimed in my application Serial No. 807,327, filed December 17, 1913, include a spring 80 acting against the end of the shaft 8 opposite from the driving pulleys to slide said shaft longitudinally, but obviously other means may be substituted if desired without departing from the spirit and scope of the present invention. In any event, it is preferable to make it necessary to positively swing the operating lever 28 from neutral to inward position and retain it in such shifted position as long as it is desired to maintain the lowering disk 15 in contact with the horizontal wheel 5 to lower the hammer. As soon as the operating lever is released, the spring 80 will swing it to its outer position and slide the raising disk 14 into engagement with the horizontal wheel, thus causing the hammer to rise.

To terminate upward movement of the hammer, screw and friction wheel 5, I provide a brake 31 above said wheel 5 and shown in the drawings as comprising a brake arm 32 having a transverse sleeve 33 intermediate of the ends of said arm for supporting the brake upon the driving shaft 8, see Figs. 1 and 4. It is to be understood that said sleeve 33 is rotatably loose upon the shaft 8 so the brake is not revolved with the shaft, and that the brake arm extends from front to back of the press substantially horizontal. Preferably said sleeve 33 is mounted upon the shaft 8 adjacent the lowering disk 15 and a second sleeve 34 in alignment with the first-mentioned sleeve 33 is positioned adjacent the raising disk 14, both of said sleeves being upon the shaft 8 between the driving disks and a suitable branch arm 29 integral with the brake arm 32 holding said sleeves 33, 34 properly spaced adjacent the respective driving disks, so as to prevent any material movement of the brake longitudinally of the driving shaft.

A brake shoe 35 of wood or any other suitable material mounted on the rear end of the brake arm 32 forms the engaging face of the brake, and it will be understood that the brake is so placed that as the friction wheel 5 is rotated and mounts upwardly, the upper surface of said wheel 5, preferably adjacent to the periphery thereof, rubs against the said brake shoe 35 and the wheel is thereby stopped. Preferably the free swinging end of the brake arm 32, away from the brake shoe 35, is connected by a depending link 36 to an arm 37 fast upon

the outer end of the transverse rock shaft 4, and which arm 37 extends partially across the front of the press to underlie at its free end said outer free end of the brake arm, 5 so that as the friction wheel 5 presses upward against the brake shoe 35 as described the front end of the brake arm 32 is simultaneously lowered, the said arm 37 depressed and the rock shaft 21 rotated to swing the 10 shifting lever 20 to disengage the raising drive-disk 14 from the friction-wheel. Said link 36 has its lower end threaded and extending loosely through an appropriate hole in said rock shaft arm 37, nuts 38, 39 on the 15 threaded rod above and below said arm providing for adjustment as to length of the link. It will be obvious, therefore, that the return of the friction wheel 5 to initial or raised position automatically disengages the 20 raising disk 14 from operative contact therewith, and this of course turns the control rod 25 and throws the hand lever 28 into middle or neutral position. In ordinary operation of the press, the horizontal wheel 25 5 is not stopped suddenly, because of its momentum, and this causes the drive disks to slide past their idle or disengaged position, so that the lowering drive disk 15 is brought into engagement with the friction 30 wheel thus causing the head or hammer 3 to start downward again. The brake is thereby released from the friction wheel 5 and the spring 30 immediately acts to press the raising disk 15 against the friction wheel 5 35 and reverse its motion again, and by the time the friction wheel engages the brake a second time its momentum is diminished enough so that the raising and lowering disks 14, 14 both remain in idle position out 40 of operative engagement with the friction wheel 5.

In order to give the sliding head or hammer a downward stroke, therefore, it is only necessary to swing the operating lever 28 45 inward, and when released the spring 30 causes an upward return of the head or hammer, throwing the lever 28 to its outer position. Means are preferably provided, however, for automatically swinging said 50 lever 28 to its outer position as soon as the hammer has completed its blow and then reversing the drive on the friction wheel to cause the same to rise. To this end a lug 40 projects from the front of the hammer 55 having its outer end tapered or sloping outwardly upward, and an adjustable lug 41 is positioned at the proper elevation upon the control rod 25 in the path of said lug adapted to be engaged and moved by said 60 lug. As shown, said dog 41 is non-tarably secured upon the control rod to project transversely therefrom, and provides a tapered engaging surface 42 sloping downwardly inward so as to coact with the tapered outer end of the lug to readily turn

or rotate the control rod. It will be understood that the dog 41 may be loosened and shifted up or down on the control rod 25 so as to adjust the length of stroke of the hammer to accommodate the work or dies 70 being used.

As so far described, the machine is started by lever 28, requiring one hand of the operator to hold the same inward against the reaction of the spring 30 and keep the lowering disk 15 in engagement with the friction wheel 5 to propel the hammer or head 3 downward. In order to leave both of the operator's hands free, however, I provide a treadle attachment so arranged that either 80 it or the lever 28 can be used, as desired. To this end a slide bar 43 extends transversely through the bed 6 from front to back of the press preferably at one side of the center, and receives the operating lever 85 28 between bifurcations or fingers 44, 44 at the front end of the bar, lying above and below said lever and connected therewith by means of a pin 45 extending vertically through said fingers and lever. The fingers 90 receive said pin in slots 46, 46 extending longitudinally of the slide bar, so that the lever may be swung inward or outward from neutral position independent of the slide bar.

Preferably the slide bar is resiliently impelled toward its rearward position, so as to swing the operating lever 28 toward the press and thereby cause the hammer to be lowered, and to this end the slide bar extends through a suitable recess 47 in the base 6 of the press and receives upon itself a helical spring 48 bearing at its rear end against a collar 49 fixed upon the slide bar and at its forward end against a fixed portion of the base, a washer 50 being shown upon the slide bar between the end of the spring and the base. Obviously any degree of compression of the spring may be secured by shifting the collar 49 upon the slide bar, and preferably the spring 48 when compressed is stronger than the spring 30 on the drive shaft 8, whereby when both springs are acting to shift the shaft 8, the spring 30 on the shaft will be overcome and the lowering disk slid into engagement with the friction wheel. It is within the scope of the present invention to provide other means or arrangements of parts than the spring 48 for resiliently tending to slide said bar 43, if desired, the one shown being 115 merely illustrative.

At its rearwardly projecting end, the slide bar 43 is provided with a lateral step which races rearwardly and is adapted to engage a detent to hold the bar forward against the power of its spring 48 and prevent the same from drawing the lever 28 inward to start the press. At the same time, said lever can be thrown inward manually by virtue of the slots 46, 46. Treadle means are provided 120

for releasing the detent, and a spring for returning it to locking position, and furthermore the engaging portions of the stop and detent are one or both beveled at their opposite sides so that they will pass in to locked engagement when the descending hammer automatically swings the lever 28 outward drawing the slide bar 43 with it. The press can therefore be started by operating the treadle to release the detent, whereupon the spring 48 forces said bar rearward and swings the lever 28; the detent returns to position as soon as pressure on the treadle is released, and thus is ready to lock the slide bar 43 in forward position after the blow is struck, preventing a second blow.

The stop and detent may be of any suitable construction, but I have shown the rear end of the slide bar 43 screw-threaded, as at 51, to receive an annular stop 52 which may be screwed on or off said slide bar to any desired position, see Fig. 2. A lock nut 53 is provided which will fix the stop upon the slide bar in adjusted position, said lock nut being small enough to leave a marginal portion of the detent exposed, and the opposite side of the stop has its edge beveled as at 54. The detent 55 slides vertically in a suitable slide plate 56 secured to the back of the bed 6 below the slide bar 43, and is limited in its upward movement by a transversely projecting pin or key 57 adapted to engage the bottom of the slide plate when the detent is raised as far as desired, it being understood that the detent extends below the slide plate. To the lower end of the detent is connected a treadle 58, (see Fig. 1), positioned and adapted to receive the operator's foot, and on the rod 59 herein shown connecting said lower end of the detent to the treadle is a spring 60 bearing at its upper end against a collar 61 fixed on the rod and at its other end bearing against a transverse shoulder 62 upon the lower end of a depending bracket 63 fixed to a stationary portion of the press as by bolting the same to the slide plate 56 as shown. This spring is made strong enough and held under sufficient compression to retain the treadle and detent 55 normally in raised position, and the upper end of the detent is properly beveled so that when the slide bar is drawn forward, the stop 52 slides over the detent past the same, at which time the detent moves upwardly behind the stop and prevents rearward movement of the slide bar 43 until the treadle is again depressed by the operator. By this construction, the operator may depress the treadle 58 with his foot, allowing the slide bar 43 to move rearwardly, after which he may remove his foot from the treadle. Rearward movement of the slide bar 43 draws the operating lever 28 inward, rotates the control rod 25 and

causes the lowering disk 15 to engage and rotate the friction wheel 5, thereby lowering the hammer 3. As the hammer approaches its lowered position, the lug 40 thereon engages and swings the dog 41 on the control rod, thereby rotating the control rod and the operating lever 28 to outer position. As the operating lever is swung outward, however, it draws the slide bar to its forward position and the stop 52 is engaged again by the detent 55 to hold the slide bar from being moved rearwardly again under the action of its spring 48. Obviously this action takes place while the lug 40 and dog 41 are in engagement, and as the operating lever is rotated from inner to outer position, the lowering disk is removed from contact with the friction wheel 5 and the raising disk 14 brought into contact with the friction wheel and held there under action of the spring 30 on the shaft 8, thereby causing the hammer to rise until the brake 31 is engaged by the friction wheel and the driving disks and operating lever returned to neutral position, as has been described.

Means are preferably provided for adapting the press to run continuously, that is, so the direction of movement of the hammer is reversed at the upper end of its slideway and the hammer caused to descend immediately. This continuous operation may be obtained in any desired manner, but in the drawings I have shown means comprising a friction drum or disk 64 non-rotatably secured to the lower end of the control rod 25, below the base 3 of the frame, with a brake band 65 encircling the periphery thereof and adapted to frictionally resist rotation of said drum. Said band is suitably supported on the frame, as by bolting at 66, see Fig. 6, and is transversely cut or separated at a convenient peripheral point, as at 67, radial ears 68, 68 being formed upon the adjacent ends at said cut. Extending through said ears in a direction transverse to the cut and tangent to the band, is a bolt 69 provided at one end with adjusting nuts 70, 70, and at the other end having a handled cam 71 pivoted therein, it being understood that the adjusting nuts and the cam are positioned upon opposite sides of the ears 68, 68. The nuts may be adjusted upon the bolt, so that the cam may be swung in one direction to contract the brake band and cause frictional engagement with the drum 64, and in the other direction to allow the brake band to expand and permit free rotation of the drum. With the cam swung so as to cause frictional engagement of the band with the drum, the control rod will be held in any position to which it is turned, that is, sufficient frictional resistance is created to counteract the spring 30 upon the drive shaft 8, so that in operation of the press as the fric-

tion wheel 5 is raised to its uppermost position and thereby shifts the lowering disk 15 into engagement with itself, the spring 30 is prevented from moving the drive disks back into neutral or idle position, and the hammer will be lowered again. Obviously the dog 41 will operate by reversing the position of the control rod when the hammer approaches its lowest position, so that the drive disks will then operate to raise the hammer again, and so on. Furthermore, the 10 detent 55 engages the stop 52 and the slide bar 43 remains stationary, the slots 46, 46 therein allowing the operating lever 28 and control rod 25 to move to their opposite extreme positions independent of the foot treadle mechanism.

Any time the operator wishes to stop the machine he may swing the operating lever 28 to its neutral position by hand, thus throwing the drive disks out of engagement with the friction wheel at any period of the stroke of the hammer desired. If he desires to stop the machine at the upper end of the 20 stroke of the hammer, and discontinue the continuous or automatic operation thereof, he may throw the handled cam 71 to release the frictional contact of the brake band and drum, so that the spring 30 upon the drive 25 shaft will swing the operating lever 28 into neutral position when the hammer is up.

By the construction thus described, it will be obvious that my improved press can be operated in almost any desired manner, so as to most conveniently and expeditiously perform various kinds of work and lend itself to the rapid production of all kinds of stamped articles.

The blow delivered by the hammer stamps 40 the blank into the lower die, and in order to remove the work therefrom I provide removing or knock-out means next to be described and best shown in Fig. 5 of the drawings. The lower die is provided at its 45 center with a vertically disposed plunger 72 having a head 73, the top of which forms a portion of the engraved upper face of the die. Said head is larger than the remaining portion or stem of the plunger and the 50 die is correspondingly recessed, so that a suitable shoulder is formed to retain the head 73 in proper position as the blank is stamped, but allowing the plunger to be raised after the stamping operation so as to dislodge the work. The stem of the plunger 55 depends into an enlarged recess 74 at the base of the die, and overlies the upper end of a vertically disposed rod or knocker 75 which is slidable through the base or bed 6 of the press and is pivoted at its lower end to a lever 76 intermediate the ends thereof. The said lever 76 is preferably pivoted in a suitable bracket 77, bolted or otherwise secured to the under side of the base of the 60 press at the front thereof, and extends rear-

wardly substantially horizontal with its other end pivotally connected to an upwardly extending trip rod 78, arranged at the rear of the press. The upper end 79 of this rod is bent or inclined away from the 70 press at a suitable angle, shown in the drawings as about forty-five degrees, and said end slides through a suitable guide 80 to the frame of the press. I have shown such guide a fork with its arms 81 lying on opposite sides of the inclined end 79 transverse thereto and receiving a transverse pin 82 outside the rod to prevent its escape; the bottom of the recess between the arms forms the other side of the slideway for the bent end, being preferably parallel to said bent end. Any other suitable construction can be employed however, so long as it insures that when the trip rod is slid upward its upper end also moves laterally outward from the press and when it is slid downward its upper part moves laterally inward toward the press.

At a suitable point on the trip rod 78 is pivoted a trip which normally projects laterally therefrom toward the press and is 90 adapted to be engaged by a finger 83 on the hammer as said hammer moves upward, said parts being arranged so that the finger will pass the trip idly as the hammer moves downward. The purpose of this construction is to have the hammer as it starts upward after delivering a blow engage the trip upon the trip rod and raise said trip rod so as to operate the knock-out means for dislodging the piece of work from the 100 lower die; as the trip rod is raised however its upper part swings outward as above described so that the trip and finger on the hammer disengage, allowing the hammer to move on upward while the trip rod and 105 knock-out means drop back to normal lowered position.

The particular form of trip which I have shown comprises a tubular body 84 pivoted on the rod by cross-pin 85 and having a lip 86 projecting toward the press or hammer. The side wall of said tubular body is slotted below said lip 86 as at 87 and suitably recessed outside the trip rod above the pin 85, as at 88 so as to allow the trip to swing outward, and a spring 89 is provided to normally hold the trip against such swinging. When the hammer moves upward its finger 83 engages the lip 86 and carries the trip rod with it until they are disengaged by lateral movement of the trip rod, but when the hammer goes down the trip swings idly outward under the impact of the finger 83, as will be understood. Obviously any other suitable form of trip could be employed if 120 desired.

A suitable stop is provided, here shown as a stirrup 90 depending from the base 6 of the press, to limit downward movement of the knock-out mechanism and insure the 125

trip being in proper position to be engaged by the hammer on its up-stroke. Obviously by the knock-out means which I have described, a piece of work may be removed 5 from the die as the hammer rises, but said removing means is returned to normal idle position before the hammer reaches the upper end of its stroke, so that there is nothing to interfere with placing another blank 10 upon the lower die to receive its impression as the hammer again descends.

It will be understood that wear between the surface of the drive disks and the periphery of the friction wheel 5 necessitates an occasional adjustment of said drive 15 disks upon the shaft 8 in order to act properly and for this purpose I have shown the means illustrated in detail in Fig. 8. The shaft 8 and hub 91 of the drive disk provide 20 a keyway adapted to receive a key 92 against which a set screw 93 carried by said hub is adapted to be grasped when the drive disk is brought into position longitudinally 25 of the shaft. Obviously there will be no strain upon the drive disk to slide it toward the friction wheel 5, and to resist its movement in the other direction, the shaft is threaded as at 94 and provided with a nut 95 and lock-nut 96 which can obviously be 30 set wherever desired within the limits of the threaded portion 94. This provides a simple and effective means of holding the drive disk rigidly upon the shaft 8 and yet enabling it to be adjusted as desired.

Obviously detail modifications may be 35 made in manufacturing my improved press without departing from the spirit and scope of the invention, and I do not wish to be understood as restricting myself except as 40 required by the following claims when construed in the light of the prior art.

Having thus described the invention, what I claim is—

1. In a press, a frame, & screw mounted in 45 said frame, a friction wheel on said screw, drive disks adapted to engage the edge of said friction wheel, a rotatable control rod, means connecting said drive disks with said control rod whereby they are shifted into 50 and out of engagement with the friction wheel by turning the control rod, and means for turning said control rod.

2. In a press, a frame, a screw mounted in 55 said frame, a friction wheel on said screw, drive disks adapted to engage the edge of said friction wheel, a rotatable control rod, means connecting said drive disks with said control rod whereby they are shifted into 60 and out of engagement with the friction wheel by turning the control rod, means for resiliently forcing the raising disk against the friction wheel, and manually operated means for turning the control rod in opposition to said resilient means.

65 3. In a press, a frame, a screw mounted in

said frame, a friction wheel on said screw, drive disks adapted to engage the edge of said friction wheel, a rotatable control rod, means connecting said drive disks with said control rod whereby they are shifted into 70 and out of engagement with the friction wheel by turning the control rod, means for automatically forcing the raising disk against the friction wheel, means for manually turning said control rod to press the lowering disk against the friction wheel, and means for automatically disengaging 75 said lowering disk on the downward movement of the screw.

4. In a press, a frame, a hammer, a screw 80 mounted in said frame, for raising and lowering said hammer, a friction wheel on said screw, drive disks adapted to engage the edge of said friction wheel, a rotatable control rod, means connecting said drive 85 disks with said control rod whereby they are shifted into and out of engagement with the friction wheel by turning the control rod, means for automatically forcing the raising disk against the friction wheel, 90 means for manually turning the control rod to press the lowering disk against the friction wheel, a dog on said control rod, and a lug on the hammer adapted to engage said dog to turn the control rod on the down 95 stroke of the hammer.

5. In a press, a frame, a screw mounted in 100 said frame, a friction wheel on said screw, drive disks adapted to engage the edge of said friction wheel, a rotatable control rod, means connecting said drive disks with said control rod whereby they are shifted into 105 and out of engagement with the friction wheel by turning the control rod, means for turning said control rod to force the lowering disk against the friction wheel when the screw is raised, and means for automatically forcing the raising disk against the friction wheel when the screw is lowered.

6. In a press, a frame, a screw mounted 110 in said frame, a friction wheel fast on said screw and movable therewith, a shaft extending diametrically of said friction wheel adjacent its uppermost position, drive disks on said shaft adapted to engage the edge of 115 said friction wheel, a lever for shifting said drive disk shaft longitudinally to throw said disks into and out of engagement with the friction wheel, a rotatable control rod, a crank arm on said rod, means connecting 120 said crank arm to said shifting lever, and means for turning said control rod.

7. In a press, a frame, a screw mounted 125 in said frame, a friction wheel fast on said screw and movable therewith, a shaft extending diametrically of said friction wheel adjacent its uppermost position, drive disks on said shaft adapted to engage the edge of 130 said friction wheel, a lever for shifting said drive disk shaft longitudinally to throw said

disks into and out of engagement with the friction wheel, a control rod pivotally mounted at the front of the frame in upper and lower bearings thereon, a crank arm on said control rod above its upper bearing, means connecting said crank arm to said shifting lever, and an operating lever on said control rod at the base of the press.

8. In a press, a frame, a screw mounted in said frame, a friction wheel fast on said screw and movable therewith, a shaft extending diametrically of said friction wheel adjacent its uppermost position, drive disks on said shaft adapted to engage the edge of said friction wheel, a lever for shifting said drive disk shaft longitudinally to throw said disks into and out of engagement with the friction wheel, a brake arm fulcrumed on said drive disk shaft, a brake at the end of said arm on one side of the shaft, means connecting the end of the arm on the other side of the shaft with said shifting lever, whereby the raising disk is disengaged from the friction wheel when the screw rises, and means for throwing said raising disk into engagement with the friction wheel on the downward movement of the screw.

9. In a press, a frame, a screw mounted in said frame, a friction wheel fast on said screw and movable therewith, a shaft extending diametrically of said friction wheel adjacent its uppermost position, drive disks on said shaft adapted to engage the edge of said friction wheel, a lever for shifting said drive disk shaft longitudinally to throw said disks into and out of engagement with the friction wheel, a brake arm fulcrumed on said drive disk shaft adjacent one of the drive disks, a brake at the end of said arm on one side of the shaft, a secondary arm extending from said brake to the shaft adjacent the other drive disk, means connecting the end of the arm on the other side of the shaft with said shifting lever, whereby the raising disk is disengaged from the friction wheel when the screw rises, and means for throwing said raising disk into engagement with the friction wheel on the downward movement of the screw.

10. In a press, a frame, a screw mounted in said frame, a friction wheel fast on said screw and movable therewith, a shaft extending diametrically of said friction wheel adjacent its uppermost position, drive disks on said shaft adapted to engage the edge of said friction wheel, a rock shaft, a lever fast on said rock shaft for shifting said drive disk shaft longitudinally to throw said disks into and out of engagement with the friction wheel, a swinging brake projecting into the path of movement of the friction wheel and adapted to be engaged by said friction wheel upon upward movement thereof, means connecting said brake to said rock shaft to operate the shifting

lever upon upward movement of the screw, and means for operating said shifting lever upon downward movement of the screw.

11. In a press, a frame, a screw mounted in said frame, a friction wheel on said screw, drive disks adapted to engage the edge of said friction wheel, a rotatable control rod, means connecting said drive disks with said control rod whereby they are shifted into and out of engagement with the friction wheel by turning the control rod, a hand lever on said control rod, a slide bar pivotally connected to said lever, spring means for actuating said slide bar to start the press, means for automatically stopping the press, and detent means for automatically locking said slide bar in idle position.

12. In a press, a frame, a screw mounted in said frame, a friction wheel on said screw, drive disks adapted to engage the edge of said friction wheel, a rotatable control rod, means connecting said drive disks with said control rod whereby they are shifted into and out of engagement with the friction wheel by turning the control rod, a hand lever on said control rod, a slide bar pivotally connected to said lever, spring means for actuating said slide bar to start the press, means for automatically stopping the press, and detent means for automatically locking said slide bar in idle position, and a foot treadle for releasing said detent means.

13. In a press, a frame, a screw mounted in said frame, a friction wheel on said screw, drive disks adapted to engage the edge of said friction wheel, a rotatable control rod, means connecting said drive disks with said control rod whereby they are shifted into and out of engagement with the friction wheel by turning the control rod, a hand lever on said control rod, spring controlled means for actuating said hand lever to start the press, means for automatically swinging said lever to stop the press, and detent means for automatically locking said spring actuated means in idle position.

14. In a press, a frame, a screw mounted in said frame, a friction wheel on said screw, drive disks adapted to engage the edge of said friction wheel, a rotatable control rod, means connecting said drive disks with said control rod whereby they are shifted into and out of engagement with the friction wheel by turning the control rod, a hand lever on said control rod, spring controlled means for actuating said hand lever to start the press, means for automatically swinging said lever to stop the press, detent means for automatically locking said spring actuated means in idle position, and a foot treadle for releasing said detent means.

15. In a press, a frame, a screw mounted in said frame, a friction wheel on said screw, drive disks adapted to engage the edge of said friction wheel, a rotatable control rod,

means connecting said drive disks with said control rod whereby they are shifted into and out of engagement with the friction wheel by turning the control rod, a hand lever on said control rod, spring controlled means for actuating said hand lever to start the press, and means for automatically swinging said lever to stop the press, both said last-mentioned means when idle leaving the hand lever free to be manually operated.

16. In a press, a frame, a screw mounted in said frame, a friction wheel on said screw, drive disks adapted to engage the edge of said friction wheel, a rotatable control rod, means connecting said drive disks with said control rod whereby they are shifted into and out of engagement with the friction wheel by turning the control rod, a hand lever on said control rod, a slide bar having a slot and pin connection with said lever, spring means for actuating said slide bar to start the press, detent means for automatically locking said slide bar in idle position so that the lever can be manually operated by virtue of the slot and pin connection, and means for automatically stopping the downward movement of the screw.

17. In a press, a frame, a screw mounted in said frame, a friction wheel on said screw, drive disks adapted to engage the edge of said friction wheel, a rotatable control rod, means connecting said drive disks with said control rod whereby they are shifted into and out of engagement with the friction wheel by turning the control rod, a hand lever on said control rod, a slide bar having a slot and pin connection with said lever, spring means for actuating said slide bar to start the press, and detent means for automatically locking said slide bar in idle position so that the lever can be manually operated by virtue of the slot and pin connection.

18. In a press, a frame, a screw mounted in said frame, a friction wheel on said screw, drive disks adapted to engage the edge of said friction wheel, a rotatable control rod, means connecting said drive disks with said control rod whereby they are shifted into and out of engagement with the friction wheel by turning the control rod, a hand lever on said control rod, a slide bar having a slot and pin connection with said lever, spring means for actuating said slide bar to start the press, an adjustable stop on said slide bar, a detent adapted to automatically engage said stop and lock the slide bar in idle position on the upward movement of the screw, means for automatically reversing the screw on its downward movement, and means for releasing said detent from said stop.

19. In a press, a frame, a screw mounted in said frame, a friction wheel on said screw,

drive disks adapted to engage the edge of said friction wheel, a rotatable control rod, means connecting said drive disks with said control rod whereby they are shifted into and out of engagement with the friction wheel by turning the control rod, a hand lever on said control rod at the base of the press, a slide bar having bearings in said base and a slot and pin connection with said lever, a spring within the base of the press adapted to move said slide bar to start the press, detent means for automatically locking said slide bar in idle position so that the lever can be manually operated by virtue of the slot and pin connection, means for releasing said detent to start the press, and means for automatically operating said hand lever to reverse the screw on its downward movement.

20. In a press, a frame, a screw mounted in said frame, a friction wheel on said screw, drive disks adapted to engage the edge of said friction wheel, a rotatable control rod, means connecting said drive disks with said control rod whereby they are shifted into and out of engagement with the friction wheel by turning the control rod, means for turning said control rod, spring means tending to engage the raising disk with the friction wheel, brake means adapted to act in conjunction with said spring means at the end of the upward movement of the screw to throw both drive disks into idle position, means for counteracting said spring means so as to cause the press to reverse at the end of the up' movement of the screw, and governing means for throwing said counteracting means into or out of operation as desired.

21. In a press, a frame, a screw mounted in said frame, a friction wheel on said screw, drive disks adapted to engage the edge of said friction wheel, a rotatable control rod, means connecting said drive disks with said control rod whereby they are shifted into and out of engagement with the friction wheel by turning the control rod, means for turning said control rod, spring means tending to engage the raising disk with the friction wheel, means adapted to act in conjunction with said spring means at the end of the upward movement of the screw to throw both drive disks into idle position, and means for counteracting said spring means so as to cause the press to reverse at the end of the up stroke of the hammer.

22. In a press, a frame, a screw mounted in said frame, a friction wheel on said screw, drive disks adapted to engage the edge of said friction wheel, a rotatable control rod, means connecting said drive disks with said control rod whereby they are shifted into and out of engagement with the friction wheel by turning the control rod, spring means for turning said control rod,

- means tending to engage the raising disk with the friction wheel, means adapted to act in conjunction with said spring means at the end of the upward movement of the 5 screw to throw both drive disks into idle position, and means for braking the turning of said control rod so as to counteract said spring means and cause the press to reverse at the end of the upward movement of the 10 screw.
23. In a press, a frame, a screw mounted in said frame, a friction wheel on said screw, drive disks adapted to engage the edge of said friction wheel, a rotatable control rod, means connecting said drive disks to said control rod whereby they are shifted into and out of engagement with the friction wheel by turning the control rod, means for turning said control rod, spring means 15 tending to engage the raising disk with the friction wheel, means adapted to act in conjunction with said spring means on the upward movement of the screw to throw both drive disks into idle position, means for 20 braking the turning of said control rod so as to counteract said spring means, and a cam for throwing said braking means into and out of engagement.
24. In a press, a frame, a screw mounted 25 in said frame, a friction wheel on said screw, drive disks adapted to engage the edge of said friction wheel, a rotatable control rod, means connecting said drive disks to said control rod whereby they are shifted into and out of engagement with the friction wheel by turning the control rod, means for turning said control rod, spring means 30 tending to engage the raising disk with the friction wheel, means adapted on upward movement of the screw to throw the raising disk out of and the lowering disk into contact with the friction wheel, a drum on 35 said control rod, a brake band for said drum, and means for engaging and releasing said brake band and drum.
25. In a press, a frame, a screw mounted 40 in said frame, a friction wheel on said screw, drive disks adapted to engage the edge of said friction wheel, a rotatable control rod, means connecting said drive disks to said control rod whereby they are shifted into and out of engagement with the friction wheel by turning the control rod, means for turning said control rod, spring means 45 tending to engage the raising disk with the friction wheel, means adapted on upward movement of the screw to throw the raising disk out of and the lowering disk into contact with the friction wheel, a drum on said control rod, a brake band for said drum, and means for engaging and releasing said brake band and drum.
26. In a press, a frame, a screw mounted 50 in said frame, a friction wheel on said screw, drive disks adapted to engage the edge of said friction wheel, a rotatable control rod, means connecting said drive disks to said control rod whereby they are shifted into and out of engagement with the friction wheel by turning the control rod, means for turning said control rod, spring means 55 tending to engage the raising disk with the friction wheel, means adapted on the upward movement of the screw to throw the raising disk out of and the lowering disk into contact with the friction wheel, a drum on said control rod, a brake band for said drum, and means for engaging and releasing said brake band.
27. In a press, a frame providing a bed 60 for a lower die, a hammer adapted to carry an upper die, means for raising and lowering said hammer, knock-out means on the base of said frame for dislodging the work from the lower die, a trip rod extending upward from said knock-out means with an outwardly inclined upper end portion extending through a slideway on the top of the frame, and a trip on said trip rod adapted to be engaged by the hammer on its upward movement to slide said rod upward.
28. In a press, a frame providing a bed 65 for a lower die, a hammer adapted to carry an upper die, means for raising and lowering said hammer, knock-out means on the base of said frame for dislodging work from the lower die, a trip rod extending upward from said knock-out means at one side of the press, guide means for said trip rod on the top of the frame adapted to swing 70 its upper end outward as it rises, and a trip on said trip rod adapted to be engaged by the hammer on its upward movement to raise said rod.
29. In a press, a frame, a screw mounted 75 in said frame, a friction wheel fast on said screw and movable therewith, a shaft extending diametrically of said friction wheel adjacent its uppermost position, drive disks on said shaft adapted to engage the edge of 80 said friction wheel, key means between each of said drive disks and the shaft, and a lock nut on said shaft at the opposite side of each drive disk from the friction wheel.
